SUPPORTING MEANS FOR PRESS PLATENS

Southard N. Baldwin, Green Ridge, Pa., assignor
to The Baldwin Locomotive Works, a corpora-
tion of Pennsylvania

Application August 8, 1947, Serial No. 767,635.

7 Claims. (Cl. 18—16)

1

This invention relates generally to platen presses which employ a plurality of platens or plates for applying in a well-known manner pressure and heat simultaneously to moldable sheet-like material, and more particularly to improvements for supporting the platens in different spaced relations to each other and for varying the length of the stroke of the moving platen in accordance with such spacing of the platens.

When a press of this type stands open, it is desirable that the platens should be spaced apart only sufficiently to receive conveniently a new charge of material. If the platens are spaced too far apart, then an excess amount of time and power is required to open and close the platens. Inasmuch as the thickness of material may vary from job to job it is desirable to be able to adjust the spacing of the platens to suit the material. As the press is closed, the platens, commencing with the lowest one, are successively lifted off their respective supporting members by an upwardly moving platen, attached to the ram of the press until all platens have been so removed from their supports and each sheet of material brought into contact with the platen immediately above it when compression of the material begins. As the press is opened, the reverse action takes place. The platens move downwardly as the moving platen is lowered by the ram and are deposited successively, beginning with the uppermost platen, on their respective supporting members until all the platens have been so returned to their original spaced positions. Various devices and arrangements, such as, for example, saddles, spacer blocks and stephangers, have been employed to provide adjustable platen supporting means that are designed to space the platens a predetermined distance apart. Such schemes, however, have proved cumbersome and inadequate in many instances, do not provide for close adjustments of the platens and, in addition, require the complete or partial removal from the press of the supporting members and the use of tools to accomplish this end. After depositing the lowermost platen on its supporting members, as above described, the moving platen continues downwardly to the end of its maximum down-stroke. This latter portion of the downstroke of the moving platen and the corresponding upstroke thereof form no useful purpose in the operation of the press and are therefore a waste of power and time. When the plates are spaced far apart these ineffective portions of the moving platen stroke are relatively short but as the plates are

2

spaced closer together such strokes increase in length and in a press providing for close adjustments of the platens, these lengthy and ineffective strokes become a consideration in the economical operation of the press.

An object of my invention is to provide improved platen supporting means that allows the platens to be adjusted in relatively small increments, preferably in uniform small fractions of the maximum distance of adjustment.

Another object is to provide improved platen supporting means of the foregoing type having the supporting elements of ample strength and capacity but without having the supporting elements for adjacent platens interfere with each other.

A further object of my invention is to provide improved platen supporting means that is relatively simple and economical in construction, 20 operation and maintenance and allows the platens to be adjusted quickly and easily to their various positions.

A still further object is to provide control means for the moving platen that are adjustable according to a predetermined spacing of the adjustable platens to limit the maximum stroke of the moving platen to a stroke that will merely raise and lower the adjustable platens, no matter what the spaced relation of the adjustable platens might be.

Other objects and advantages will be more apparent to those skilled in the art from the following description of the accompanying drawings in which:

35 Fig. 1 is a front elevation of a steam platen press of the type described, employing my invention;

Fig. 2 is a perspective of part of the left-hand corner of said press, as viewed in Fig. 1;

40 Fig. 3 is a perspective of one of the platen guides showing its attachment to an adjustable platen;

Fig. 4 is a cross sectional plan view of said press along the line 4—4 of Fig. 1;

45 Figs. 5 and 6 are plan views of the two types of supporting fingers employed in my invention;

Figs. 7 and 8 are elevational views of said types of supporting fingers; and

Fig. 9 is a vertical sectional view of my adjustable moving platen control means.

In the particular embodiment of the invention which is disclosed herein merely for the purpose of illustrating one specific form among possible others that the invention might take in practice,

55 I show in Fig. 1 a usual steam platen press hav-

ing a cylinder 1, a ram 2, a moving platen 3 affixed to the ram, an upper crosshead or platen 4 supported in the usual and well-known manner on four vertical tension columns 5 whose lower ends are connected to the cylinder, and a plurality of vertically adjustable hot plates or steam platens 6. These plates are maintained in vertical alignment by platen rings 7 affixed to the corners of each adjustable platen and slideable on the tension columns. The rings 7 for each column are divided into two general groups 8 and 9, Fig. 1, respectively having supporting lugs 10 to 14 and 15 to 18. The lugs within a group, certain of which are shown in Fig. 2, are of different lengths, and the lugs 15-18 of the upper group are shown preferably tangential to the rings while the lugs 10-14 of the lower group are offset with respect to the upper group of lugs. Cooperating with these lugs to support the same are two groups of supporting elements consisting of a lower group 19 to 23 and an upper group 24 to 27. Each of said elements has an annular collar 28 vertically and rotatably movable on finger support columns 29, 30, 31 and 32, Fig. 4, located at each of four corners of the press parallel and adjacent to the tension columns 5. It will be understood that the platen lugs and supporting fingers therefor are duplicated at each of the four corners of the press and hence the description for one corner will suffice for all. The annular collars 28 of the lower group have supporting fingers 33-42 extending from opposite sides of their respective collars and, as shown in Fig. 2, are tangential to opposite sides thereof. The oppositely extending fingers of each collar are of the same length but the length of the fingers of successive collars are of different length. Similar supporting fingers 43-50, Fig. 1, are provided on the collars of the upper group but as seen in Fig. 2, and particularly Figs. 5 and 6, these fingers are tangential to their collars on the opposite diagonal side to that of the fingers 33-42 of the lower group. The pair of fingers of each collar have landings 51 and 52, Figs. 5 to 8, at slightly different levels, the landing 52 being a recess and being preferably halfway between adjusting holes 53 in the columns 29 to 32. The collar is supported by a single swivel bolt 54 of well-known form having a pivotal cross latch 55 to permit ready removal from or insertion in a suitable hole of the collar aligned with holes 53.

Operation—Platen adjusting means

When the press is in the open position as shown in Fig. 2 each platen is supported upon its respective supporting fingers. To close the press, the ram 2 and ram platen 3 will successively lift the platens off their supporting fingers. However, there will be no interference between the platen lugs and the supporting fingers because of the different lengths of the lugs and fingers and the offset relation of the same. For instance, as shown in Fig. 2, lug 13 will follow along a dotted line 56 which clears the end of finger 41 and then because of the lateral offset relation between lug 13 and finger 43 will clear the latter by passing back of the same. Similarly lug 13 will pass behind the remaining offset fingers of the upper group thereof. Lug 14 will similarly pass alongside of the offset fingers 43, 45, etc., of the upper group as indicated by the dotted line 57. Lugs 15, 16, etc., of the upper group will clear the ends of the successively shorter fingers 45, 47 etc. of the upper group as

shown by dotted lines 58a. Thus, it is seen that even though the supporting fingers are of different lengths and even though they are quite close together there will never be any interference between the lugs and the various supporting fingers. This arrangement allows a high degree of flexibility in adjusting the supporting fingers to various positions even though they might be very close to each other or the incremental change in spacing might be quite small. The collar 28 by engaging columns 29 to 32 on their opposite sides insures maximum supporting strength even though only a single pin 54 is used. The use of a single pin allows the collars to be of very small axial length thereby in turn permitting the collars to be brought very close to each other. The pin also functions as a fulcrum to assist in having the collars take a gripping bite on columns 29 to 32 due to the cantilever action of the supporting fingers. While I have preferably shown the collars of circular form, yet the foregoing principle can be accomplished with other equivalent shapes. To obtain very small adjustments of platen spacings, the supporting pins 54 may be removed and the finger collar turned to 180° to bring the higher landing levels thereof into cooperation with the platen supporting lugs. The operation of such higher landing fingers with respect to having the supporting lugs clear the same is identical to that previously described for the fingers with the recessed lower landings. This is because fingers 34, 36, 38, 40 etc. are respectively of the same length as fingers 33, 35, 37, 39 etc. and are diagonally opposite in the same relation to the collar as fingers 33, 35, 37, 39, etc., so that when the collar is rotated 180° the same relationship is maintained with respect to the supporting lugs. It will be noted that the recessed landing 52 lies midway between any two successive holes 53 of the finger supporting columns 29 to 32 thereby permitting the column holes to be placed sufficiently far apart to obtain necessary strength but without sacrificing the ability to have a landing at a level intermediate of adjacent holes.

Stroke limiting mechanism

In view of the close adjustments of the adjustable platens possible with my improved platen supporting means, as above described, a large part of the maximum stroke of the moving platen would be ineffective when the adjustable platens are closely spaced, for only a relatively small portion of such stroke would be used to raise and lower the platens. To overcome this in cooperation with my improved platen supporting means with its highly variable adjustable relation, I provide control means for the moving platen, shown in Figs. 1 and 8. Welded or otherwise rigidly affixed to moving platen 3 is the upper end of a vertical tube 58 having a hole 59. A rod 60 slideable within tube 58 has a series of holes 61 spaced apart a distance equal to the sum of all the minimum spacings between the platens. A bolt 62 may be inserted in any of the aligned holes of the tube and rod. Screw-threaded into the lower end of rod 60 is a threaded shank 63 of an adjusting screw 64 having an enlarged head 65 with usual spanner recesses and a lock nut 66. This support for the moving platen is adjustable by removing bolt 62, sliding the rod in or out of the tube until hole 59 of the tube registers with one of the equally spaced holes 61 that will give the rod and tube assembly the required length, and then re-inserting the bolt.

in these registering holes. After the moving platen has deposited the lowest adjustable platen on its finger supports, it continues to move downwardly until the moving plate or a steam plate affixed thereto is spaced from the last adjustable platen a distance equal to the space between any two adjacent platens. At this point head 65 of adjusting screw 64 comes into contact with a horizontal surface 67 of the cylinder and stops the moving platen from further downward movement, holding the moving platen at this point in readiness to begin its upward stroke when the press is again to be closed. As adjustable platens are spaced closer together or farther apart, a corresponding adjustment of the moving platen control means is of course necessary. If a number of control means are circumferentially disposed about and affixed to the sides of a moving platen of a press, the moving platen or a steam plate affixed thereto can be adjusted to a horizontal plane if necessary by opening the press until heads 65 of adjusting screws 64 come into contact with horizontal surfaces 67, then loosening locking nuts 66 and turning heads 65 to the right or left to lower or raise the moving platen as may be indicated by a spirit level on the top of the moving platen.

From the disclosure herein, it is seen that I have provided a simple, expedient and highly flexible platen supporting means which can be adjusted without the aid of tools and without removing any part from the press, except a small bolt, and which can be easily and speedily adjusted to space the platens vertically from zero to a maximum distance in uniform and relatively small fractions of such maximum distance and, in conjunction with said platen supporting means, moving platen control means are adjustable to limit the maximum stroke of the moving platen to a stroke whose entire length will be used to raise and lower the adjustable platens no matter in what spaced relation they may be.

It will of course be understood by those skilled in the art that various changes may be made in the construction and arrangement of parts without departing from the spirit of the invention as set forth in the appended claims.

I claim:

1. A platen press having a plurality of platens each provided with a supporting portion, a column, means contacting opposite sides of said column and having an element extending laterally therefrom to engage said platen supporting portion, and means whereby the weight of the platen tends to tilt the contacting means into a frictional supporting contact with the column on both sides thereof.

2. In a platen press having a plurality of vertically adjustable platens, platen supporting means comprising two groups of supporting lugs affixed to the platens, the lugs of one group being offset laterally with respect to the lugs of the other group, and the lugs of each group being progressively shorter beginning with the uppermost lug of each group, a column associated with both groups of lugs, two groups of vertically and rotatably adjustable collars mounted on the column, each collar having supporting fingers to engage the supporting lugs of both groups, the fingers of the collars of one group being offset laterally with respect to the fingers of the collars of the other group, and the fingers of the collars of each group being progressively longer beginning with the finger of the uppermost collar of each group, so that when the press is closed and opened each

lug will pass the fingers located thereabove without interference therefrom, and means for releasably securing the collars to the columns so as to space the adjustable platens any predetermined distance apart.

3. In a platen press having a plurality of vertically adjustable platens and platen supporting means, as defined in claim 2, further characterized in that each collar of both groups of adjustable collars has two oppositely extending supporting fingers of equal length, which fingers are provided with landings at different levels, so that a lug in one position of the fingers is supported at one level and in another position of the fingers is supported at a different level.

4. In a platen press having a plurality of vertically adjustable platens and platen supporting means, as defined in claim 2, further characterized in that the fingers of collars of one group extend outwardly from the ends of a diagonal through the collar, and the fingers of collars of the other group extend outwardly from the ends of the opposite diagonal through the collar.

5. In a platen press having a plurality of adjustable platens which are raised and lowered by a moving platen actuated by a ram within a cylinder, moving platen control means comprising a tube affixed to the moving platen and having a transverse hole therein, a rod slideable in the tube and having a series of transverse holes registerable with the hole of the tube, and a bolt insertable in the hole of the tube and in one of the series of holes of the rod to maintain the rod and tube in immovable relationship so that on the downward stroke of the ram, the moving platen is stopped by the engagement of the rod with a horizontal surface of the cylinder at a point predetermined from the spacings of the adjustable platens.

6. In a platen press having a plurality of vertically adjustable platens, platen supporting means comprising a group of supporting lugs affixed to the platens, said lugs being progressively shorter beginning with the uppermost lug of the group, a column associated with said group of lugs, a group of vertically and rotatably adjustable collars mounted on said column and each collar having supporting fingers to engage the supporting lugs, said fingers being progressively longer beginning with the finger of the uppermost collar so that when the press is closed and opened each lug will pass the fingers located thereabove without interference therefrom, and means for releasably securing the collars to the column so as to space the adjustable platens at varying distances apart.

7. The combination set forth in claim 6 further characterized in that each collar has two fingers extending in different radial directions and provided with landings at different elevations whereby by rotation of a collar without changing its vertical position presents a different platen adjustment.

SOUTHARD N. BALDWIN.
